UNITED STATES PATENT OFFICE.

LINCOLN GORSUCH, OF LAZEAR, COLORADO.

BEEHIVE.

1,099,295.

Specification of Letters Patent.

Patented June 9, 1914.

Application filed February 7, 1914. Serial No. 817,315.

To all whom it may concern:

Be it known that I, LINCOLN GORSUCH, a citizen of the United States, residing at Lazear, in the county of Delta and State of Colorado, have invented certain new and useful Improvements in Beehives, of which the following is a specification, reference being had to the accompanying drawings.

This invention relates to new and useful improvements in bee hives, and more particularly to the general structure thereof and the primary object of the invention is to provide a device of this character which is simpler in construction and more readily set up or taken down, when desired, than the hives in present use.

A further object of the invention resides in providing a means for partially removing the brood frames for inspection of the colony and a still further object resides in providing a novel form of hinged side wall for the hive.

Still another object of the invention resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a front elevation of a device constructed in accordance with my invention, with parts broken away and disclosed in section. Fig. 2 is an end elevation of the device. Fig. 3 is a top plan view thereof partly in section, the top being removed. Fig. 4 is a fragmentary section, as seen on line 4—4, Fig. 2. Fig. 5 is a section as seen on line 5—5, Fig. 1, looking in the direction of the arrow. Fig. 6 is a fragmentary sectional view through the device showing the feed box inverted. Fig. 7 is a fragmentary end view showing the front wall in its partially open position and disclosing the V-shaped plate in position. Fig. 8 is an end elevation with parts broken away and parts in section, showing the front wall of the device in its partially open position and the V-shaped plate in position with respect thereto. Fig. 9 is a per-

spective view of one of the V-shaped plates used in connection with the device. Fig. 10 is a vertical transverse section through the device showing the partition or division wall in position therein. Fig. 11 is a fragmentary top plan view showing the dividing plate in position and the top removed. Fig. 12 is a section as seen on line 12—12, Fig. 11, looking in the direction of the arrow; and Fig. 13 is a fragmentary end elevation showing the block used in connection with the dividing plate.

In describing my invention, I shall refer to the drawings in which similar reference characters designate corresponding parts throughout the several views and in which—

1 indicates a stand or base for the device, which is designed to form a rectangular housing, the upper wall thereof forming the floor proper for the hive, and secured to the upper wall of the stand, which forms the floor proper, are the cleats or bottom boards 2. Two of these cleats extend longitudinally the full length of the stand and a third cleat is secured therebetween, along one end of the device, while no cleat is provided at the opposite end, the latter end forming the entrance end of the device, as will be hereinafter and more particularly set forth. Securely mounted on the one longitudinal cleat, is a rear wall 3, and secured to the ends of the rear wall and resting on both longitudinal cleats are the end walls 4 and 5. A front wall 6 is provided for the hive, the latter having trunnions 7 projecting from the end edges, adjacent the lower edge thereof, which are loosely mounted in openings in the end walls 4 and 5. These trunnions are threaded and nuts 8 are engaged therewith, whereby to pivotally support the front wall in position between the end walls. The front edges of the end walls 4 and 5, adjacent the upper ends thereof, are provided with notches 9, which receive therein additional trunnions 10 carried on the front wall adjacent the upper edge thereof. These trunnions are also threaded and have nuts 11 engaged therewith, whereby when said trunnions are properly engaged in the notches 9, said nuts may be turned home and the front wall securely held in position between the end walls.

The end walls have the inner faces thereof offset at the front edges of the same, as

shown at 12 to provide shoulders, against which the front wall may be engaged and the inner face of the front wall is also offset, as shown at 13. The portion of the front wall between the offset ends thereof, is received snugly between the faces of the end walls and the opposite ends of the front wall rest against the shoulders provided by the offsets 12 in said end walls. The upper edges of the end walls are also offset from the inner faces thereof, as shown at 14 and the upper edges of these offset portions receive in resting engagement thereon the projections 15 of the self-spacing brood frames 16. These brood frames are of a type well known to the art and are obviously for the purpose of holding the combs. I provide a sufficient number of brood frames, (eight, as shown in the drawings), as to completely fill the hive and fit snugly against one another, when the front wall 6 is disposed to its raised or closed position and thus the customary division board which is ordinarily a worthless division, is eliminated.

It must be here stated that the additional trunnions 10 on the front wall 6, project slightly beyond the outer faces of the end walls and hook members are provided for engagement therewith, to additionally retain said front wall in upright position. To this end, the locking strips 17 are pivotally mounted on the outer faces of the end walls adjacent the upper ends thereof, said strips being provided with locking notches 18, adjacent their free ends and projecting inwardly from one of the edges thereof. These notches are adapted to receive the projecting portions of the trunnions and when the nuts on said trunnions are turned home, said locking strips will be securely retained in position on the trunnions, whereby the front wall will be securely held in position.

As previously stated, the stand 1 is of a housing-like character, the upper wall of which forms the floor proper of the hive. This upper face or wall of the stand or housing is provided with a pair of spaced openings 19 at one end thereof. A drawer 20 is slidably mounted in this latter end of the stand or base 1 and when disposed so that the same opens upwardly, the openings 19 afford communication between the drawer and the interior of the hive proper. This drawer forms a feeder for the device and is provided with a downwardly inclined wall 21, the latter being formed preferably of wire mesh and terminating slightly in advance of the one side wall of the drawer proper. The bees, when desiring to be fed, may readily crawl through the openings 19 and enter the drawer or feed member 20. In view of the inclined wall 21, it will be seen that the bees are not liable to be drowned, as is true in most of the hives now in use. When it is not desired to permit the

bees to feed, the drawer may be entirely removed and reversed, permitting the bottom of the drawer to face upwardly, thus covering the openings 19, so as to afford no exit whatsoever from the interior of the hive.

When it is desired to inspect the brood frames, the nuts 11 on the additional trunnions are slightly disengaged from the locking strips 17 and the latter raised out of engagement with the trunnions 10. The front walls 6 may then be opened. In the inspection of the device when it is not desired to entirely lower the front wall, in order to permit the same to be retained in a partially lowered position, a pair of triangularly-shaped blocks 22 are provided, the same fitting in the offsets at the ends of the front wall and in the offsets at the front edges of the end walls. Additional hook members 23 are pivotally carried on the outer faces of the end walls 4 and 5 and the same are adapted to be engaged with the trunnions 10 when the blocks 22 are properly positioned between the end walls and the front wall. When so positioned, the front wall will be locked in a partially open position, inclining upwardly and outwardly from its pivoted lower edge. The brood frames are then adapted to be drawn, one at a time, from their positions to rest upon the upper edges of the blocks 22 in an inclined position and as each brood frame is removed from its initial position, the same will be readily and quickly inspected. The complete set of brood frames may be readily replaced to their initial positions simultaneously by the forcing inwardly of the first brood frame removed and the hook members 23 may be disengaged from the additional trunnions and the blocks 22 removed, whereupon the front wall 6 may be returned to its initial locked and raised position. Of course, should any defect be found in the comb or other portion of any one of the brood frames, the same may be removed and readily replaced by a new frame at the time of inspection. Of this particular construction, which is hereabove described, as a means for inspecting the brood frames, without entirely removing the same from the hive, it is extremely important to know the fact that all of the brood frames may be returned to their initial positions simultaneously upon the forcing inwardly of the first brood frame removed. The complete operation for partially removing the frames for inspection and the return of the same to their initial positions, is a simple one, requiring but a very small amount of time and labor.

It is sometimes desirable or necessary to operate the hive in connection with but half or a portion of the number of brood frames provided therein. In order to carry out this idea, a removable wall 24 is provided,

the same being of a length slightly greater than the length of the interior of the body of the hive proper and of a height substantially equal to the height of the latter.

5 Formed on the upper portions of the side edges thereof, are tabs or projections 24^a which are adapted to be seated on the shoulders or offset portions, indicated as 14. In applying this removable wall to use, as 10 many brood frames as are desired to be used in connection therewith are permitted to remain in place in the body of the hive to abut one another from the rear wall 3 thereof. In order to apply the removable wall 15 24 in place, however, it is necessary, in view of its length, to remove the tight engagement of the side walls of the body of the hive from the bolts 7. In other words, the nuts 8 are loosened on the bolts 7 and 20 the nuts 11 loosened on the bolts 10, whereupon said side walls are forced somewhat outwardly. The removable wall 24 may then be inserted in place against the forward brood frame, so that the projections 25 or tabs 24^a thereof will rest on the shoulders or offsets 14. When the nuts 11 and 8 are properly turned home on their respective bolts, the side walls of the hive proper will, obviously bind tightly against the side edges 30 of this wall 24 and securely retain the latter in place. When so disposed, it will be seen that the brood frames will be held in proper position in the rear portion of the body of the device and a space left between the removable wall 24 and the front wall of the body of the hive. The hive is applied to use in this manner when there is a weak colony and when it is found that another frame may be used, the removable wall is 40 moved forwardly in the device sufficiently to admit of another frame being applied therein. Of course, in the moving forwardly of this wall 24, the side walls of the device must be removed from their tight 45 engagement with the bolts and nuts 7 and 8 and the bolts and nuts 11 and 10, as described above. This operation may be continued until all of the frames are applied and the removable wall 24 is then placed in 50 disuse, as the same is not necessary whatsoever when all the brood frames are in use. It will be noted that in the entrance opening of the device, there is a wide space between the removable wall and the front wall 55 of the device. In order to cover this opening, a block 25 is provided. This block is applied to the entrance space formed between the one end wall and the bottom of the hive and between the removable wall 60 and the front wall of the hive, the same being designed to abut at its one end a stop member or the like 26, projecting from the floor of the hive proper and the other end being adapted to abut the one side edge of 65 the removable wall 24, adjacent the lower

end of the latter. In this manner the portion of the hive being used is entirely inclosed.

I have also provided an improved top or covering for my device which is indicated 70 in the drawings as 27. This top is provided at its ends with the end flanges 29, the one of which is secured to the one face of the top and projects upwardly, while the other is secured to the opposite face of the top and 75 projects downwardly, as clearly shown in Fig. 1 of the drawings. It is intended, in practice, that a number of these hives shall be stacked, one on top of the other, and the function therefore of the upper flange 29 80 is to limit the inward movement of a superposed hive, while the lower cleat prevents the top or cover from being pushed off of the hive. Secured to both faces of the top 27, are the layers of roofing material indicated as 30 and, in the application of the flanges 29 to use, the same are applied after this roofing material has been applied to the top. This roofing material is preferably secured in place throughout the area of the 85 top, so as to fit tightly in place in all weather conditions.

From the foregoing description of the construction of my improved device, the manner of applying the same to use and 95 the operation thereof will be readily understood and it will be seen that I have provided an improved bee hive which is a vast improvement over hives now in use and one which is simple and durable in construction, 100 inexpensive to manufacture and one which will be very efficient and useful in operation.

While I have particularly described the elements best adapted to perform the functions set forth, it is obvious that various 105 changes in form, proportion and in the minor details of construction may be resorted to without departing from the spirit or sacrificing any of the principles of the invention.

Having thus described this invention, what I claim is:—

1. In a hive, a base member, a housing mounted thereon to form the body of the hive proper, the front wall of said body being hinged in position, a plurality of brood frames mounted in the housing, means to secure the hinged wall in closed position on the housing, triangular side plates adapted to be disposed between the forward edges of 115 the side walls of the housing and the front wall of the housing when the latter is disposed to a partially open position, and means to lock said front hinged wall in its partially open position, whereby to inspect 120 the interior of the housing.

2. In a hive, a base member, a housing mounted thereon to form the body of the hive proper, the front wall of said body being hinged at its lower end to open out- 130

wardly, means to lock said front wall in its upright and closed position on the body, brood frames movably mounted in the housing, triangularly designed side plates 5 adapted to be disposed between the forward edges of the side walls of the housing and the inner face of the front wall thereof when the latter is disposed to a partially lowered and open position, hook members pivotally 10 carried on the sides of the housing, and means carried on the hinged front wall thereof adapted to be engaged by said hook members to lock said hinged wall in its partially open position, whereby inspection 15 may be had of the interior of the housing.

3. In a hive of the class described, a base member, a housing mounted thereon designed to form the body of the hive, said base member forming the floor of said body, 20 and having openings therein within the body, said base member being also provided with a recess communicating with the interior of the body through the medium of said openings, and an invertible feeding member slidably mounted in said recess, said feeding member, when inverted, being designed to cover the openings in the base member.

4. In a hive, a base member having a recess terminating in the front wall of the same, the top of said base member being provided with openings leading to said recess, a housing mounted on said base member and designed to form the body of the hive, the 30 top of said base member forming the floor of said body, an invertible drawer slidably mounted in said recess and designed to form a feeding member when disposed in its upright position, entrance being gained to the 40 feeding member through the medium of the openings in the top of said base member, and said drawer being designed to close the aforesaid openings when the same is inverted in the recess of the base member.

45 5. In a bee hive, a base member, a housing mounted thereon comprising a rear wall, side walls secured thereto, a front wall hinged at its lower edge to the lower edges of the side walls at the forward edges thereof, said front 50 wall being adjustably and removably mount-

ed in position, means to secure said front wall in its upright and closed position, the upper face of said base forming the bottom of the housing, a plurality of brood frames supported between the side walls of said 55 housing and extending from the rear wall thereof forwardly, a removable wall operating the forward brood frame and adjustably secured in position between the side walls of said housing, and a cover for the 60 housing.

6. In a bee hive, a base, a housing mounted thereon comprising a rear wall, side walls secured thereto, a front wall hinged at its lower edge to the lower ends of the side 65 walls adjacent the forward edges thereof, means for adjustably securing said hinged front wall in its upright and closed position, the upper face of said base forming the bottom of the housing, shoulders formed on the 70 inner faces of the side walls adjacent the upper edges thereof, a plurality of brood frames supported on the shoulders of said side walls, and extending from the rear wall of the housing forwardly, a wall adapted 75 for disposition against the forward brood frame, and having lateral projections on the upper ends of the side edges thereof to rest on the shoulders of the side walls of said housing, said wall being held in position 80 under binding engagement with the side walls of the housing, and a cover for said housing.

7. A cover of bee hives comprising a body, of substantially rectangular design, 85 layers of roofing material applied to the faces thereof, a flange secured to the roofing material on one face of the body, immediately adjacent the one end edge thereof, and an additional flange secured to the roofing 90 material on the opposite face of the body, immediately adjacent the opposite end edge of said body.

In testimony whereof I hereunto affix my signature in the presence of two witnesses. 95

LINCOLN GORSUCH.
